SAMPLE CONTAINER FOR LABORATORY TESTING APPARATUS

James F. Grimshaw, Rochester, N.Y., assignor to Bausch
& Lomb Incorporated, Rochester, N.Y., a corporation
of New York

Filed June 27, 1966, Ser. No. 2,826

Term of patent 14 years

(Cl. D16—1)

FIG. 4

FIG. 2

FIG. 3

FIGURE 1 is a top view of a sample container for laboratory testing apparatus showing my new design;

FIGURE 2 is a sectional view of the sample container of FIGURE 1 taken along the line 2—2;

FIGURE 3 is a perspective view of the sample container of FIGURES 1 and 2; and

FIGURE 4 is a rear view of the sample container.

I claim:

The ornamental design for a sample container for laboratory testing apparatus, as shown.
